BUCKLE.

1,392,064.

Specification of Letters Patent. Patented Sept. 27, 1921.

Application filed July 5, 1921. Serial No. 482,396.

To all whom it may concern:

Be it known that we, JULIUS H. KINTZELE and FELIX P. KINTZELE, residing at St. Louis, Missouri, citizens of the United States, have invented a new and useful Buckle, of which the following is a specification.

This invention relates to buckles.

An object of the invention is to provide a buckle for use in connection with belts and the like, embodying a novel construction and arrangement and relationship of parts for permitting an expanding action of the buckle.

Another object of the invention is to provide a buckle of the character mentioned, in which the engaging or gripping device of the buckle is controlled by novel and efficient elements.

Other objects will appear from the following description, reference being made to the accompanying drawing, in which—

Figure 1 is a front elevation of our improved buckle.

Fig. 2 is an inner side elevation.

Fig. 3 is a view showing one of the side edges of the buckle.

Fig. 4 is a longitudinal sectional view.

Fig. 5 is an end elevation, showing the gripping or engaging device.

Fig. 6 is a view showing the controlling member for the engaging device detached from the buckle.

Fig. 7 is a view showing the coöperating controlling member to which one end of the belt is permanently secured, said member also being shown detached from the buckle.

In the embodiment shown, our improved buckle comprises a front portion 1 having its side edges turned inwardly approximately at right angles thereto to provide side flanges 2.

Near one end of the buckle, the engaging or gripping member is pivotally supported, the same comprising a plate 3 having projections 4 on its ends, engaged within holes in the flanges 2. In this way the engaging or gripper plate 3 is pivotally supported transversely of the buckle, the length of the gripper plate being nearly equal to the width of the buckle. The edge of the gripper plate which is adjacent to the front portion 1 of the buckle is provided with means effecting proper engagement with a belt passed between the gripper plate and

the front portion 1 of the buckle. As shown, the engaging means of the gripper plate includes a flange 5 turned inwardly from the gripper plate and arranged so that when stress is applied to the belt, the gripper plate 60 will be positively engaged therewith, clamping the belt firmly against the front portion 1 of the buckle.

A plate, comprising a narrow central portion 6, two arms 7 at one end of the central portion 6 pivotally connected to the edge of the gripper plate 3, and two arms 8 at the opposite end of the central portion 6, extending into slots 9 in the flanges 2, constitutes part of the controlling means of the 70 gripper plate, and also a part of the construction by which the expanding action of the buckle is obtained. The longitudinal central portion of said plate is formed with a spring housing 10, the end of which away 75 from the gripper plate is provided with an inturned portion 11 to serve as an abutment or bearing for the end of the expansion spring 12, mounted in the spring housing.

The coöperating member by which expansion is obtained is in the form of a plate, comprising a narrow portion 13 of about the same width as the narrow portion 6 of the other plate described, and a wide loop or eye 14 at one end. The narrow portion 13 of 85 said plate is formed with a spring housing 15, matching the housing 10 on the other plate, and having an abutment 16 at the inner end thereof to serve as a seat for the end of the spring 12 opposite from the seat 90 11 on the other plate. This belt connecting plate is located between the front plate 1 of the belt and the plate that is pivoted to the gripper device 3. The spring 12 is located within the housing formed in said two 95 plates as described, one end of said spring bearing against the seat 11 and the other end of said spring bearing against the seat 16. The spring is of the expansion type. One of said plates, in this case the plate 100 shown in Fig. 6, is provided with a pair of projections or tongues 17 near the arms 8. The projections or tongues 17 are clamped around the side edges of the narrow portion 13 of the coöperating plate, thereby supporting the coöperating plate for sliding movement of the buckle. Projections 18 on the sliding plate by contact with the tongues or projections 17, stop and limit expanding 105 movement of the sliding plate.

The eye or wide portion 14 of the sliding plate is of slightly greater width than the width of the front plate 1 and, by contact with the ends of the flanges 2, limit inward or contractile movement of the parts.

In use one end of the belt is secured to the eye or belt connecting portion 14 in any appropriate manner. By applying pressure to the pivoted plate 6, with a tendency to actuate said plate in a direction to compress the spring 12, the gripper plate 3 may be turned on its pivots 4 to widen the space between the gripper plate and the front plate 1 of the buckle. When this is done, the free end of the belt may be passed through the buckle, and when in proper position, will be engaged by the gripper plate when the pivoted plate 6 is released.

From the foregoing it is apparent that our invention serves all of its intended purposes and objects. The device is simple as to construction, includes a minimum number of parts, may be economically manufactured and is strong and durable.

It is apparent that the construction and arrangement may be varied without departure from the principle of the invention. We do not restrict ourselves to unessential features, but what we claim and desire to secure by Letters Patent is:—

1. A buckle, comprising a front plate, side flanges on the front plate, a gripper plate pivoted to the side flanges, a member pivoted to the gripper plate and having sliding connections with said flanges, a connecting plate supported by said member for sliding movements, and an expansion spring located between said member and said sliding plate.

2. A buckle of the character described, comprising a front plate, a flange extending inwardly from each side edge of the front plate, a gripper plate pivotally supported by said flanges, a member pivoted to said gripper plate and having sliding connection with said flanges, a sliding plate supported by said member for sliding movements, a spring seat formed between said member and said sliding plate, a spring located in said spring seat, and a part in connection with said sliding plate abutting against the ends of said flanges and constituting means for connection with a belt.

3. A buckle of the character described, comprising a front plate, side flanges in connection with the front plate, a gripper plate pivoted to the side flanges near one end thereof, a member pivoted to the gripper plate and having sliding connection with said flanges, a connecting plate supported

by said member for sliding movements, a spring located between said member and said connecting plate, and construction whereby the expansive power of said spring is exerted to actuate the gripper plate in a direction to grip a belt passed between the gripper plate and the front plate.

4. A buckle of the character described, comprising a front plate, a flange extending inwardly from each side edge of the front plate, a gripper plate pivotally supported by said flanges near one end of the front plate, a laterally extended portion on the gripper plate for engaging the belt located between the gripper plate and the front plate and having sliding connection with said flanges, a sliding connecting plate supported by said member, a spring located between said member and said sliding connecting plate, and construction whereby the power of said spring is exerted to actuate said gripper plate in a direction to engage a belt located between said plate and the front plate.

5. A buckle of the character described, comprising a front plate, a flange extending inwardly from each side edge of the front plate, a gripper plate pivotally supported by said flanges near one end of the front plate, a laterally extended portion on the gripper plate for engaging a belt located between the gripper plate and the front plate, a member pivoted to the gripper plate and having sliding connection with said flanges, a sliding connecting plate supported by said member, a spring located between said member and said sliding connecting plate, and construction whereby the power of said spring is exerted to actuate said gripper plate in a direction to engage a belt located between said plate and the front plate, with increased pressure as said sliding plate is drawn outwardly.

6. A buckle of the character described, comprising a front plate, a gripper plate pivotally supported thereby and arranged to engage a belt located between the gripper plate and the front plate, a member pivoted to the gripper plate, a sliding connecting plate supported by said member, a spring located between said member and said sliding connecting plate, construction whereby the power of said spring is exerted upon said member and said connecting plate to cause said gripper plate to engage a belt located between the gripper plate and the front plate, and means limiting outward movement of said connecting plate.
